UNITED STATES PATENT OFFICE.

FRANK C. JONES, OF TOLEDO, IOWA.

MEANS FOR REMOVING AND REPLACING WRIST-PIN BUSHINGS.

1,280,233.

Specification of Letters Patent.

Patented Oct. 1, 1918.

Application filed April 21, 1917, Serial No. 163,675. Renewed February 25, 1918. Serial No. 212,152.

To all whom it may concern:

Be it known that I, FRANK C. JONES, a citizen of the United States, residing at Toledo, in the county of Tama and State of Iowa, have invented certain new and useful Improvements in Means for Removing and Replacing Wrist-Pin Bushings, of which the following is a specification, reference being had to the accompanying drawings.

- 10 This invention relates to means for forcing out and replacing bushings, and particularly to means for forcing out old or worn bushings from hollow pistons and replacing said bushings.
- 15 The general object of the invention is to provide a very simple, easily operated device of the character described, whereby the wrist pin bushings may be forced out and new bushings forced in, without deforming
- 20 or in any way distorting the wall of the piston.

A further object of the invention is to provide a screw press for this purpose, and still another object is to provide means for supporting the wall of the piston against deformation, due to the pressure exerted in forcing in the new bushing and in this connection to provide a piston support formed of two sections, with means for expanding the sections against the annular hubs which extend inward and which surround the bushings, thus supporting the piston against deformation.

Other objects will appear in the course 25 of the following description.

My invention is illustrated in the accompanying drawings, wherein:

Figure 1 is a side elevation of my device showing it in use in forcing out an old bushing, the piston and bushing being shown in section.

Fig. 2 is a sectional view on the line 2—2 of Fig. 1 showing the device applied to the forcing in of a new bushing.

Fig. 3 is a perspective view of the extension piece.

Fig. 4 is a perspective view of the head 20.

Fig. 5 is a perspective view of one of the expanding blocks.

Fig. 6 is a perspective view of both expanding blocks looking at the inner faces thereof.

Referring to these drawings, it will be seen that my device comprises a bed 10, 55 which is formed upon its upper face with

a transversely concave seat 11, having the curvature of a piston. Below this seat, the bed is cut away as at 12 and extending through the bed from the seat 11 to the cut-away portion 12 is an opening 13, which is greater in diameter than the diameter of the bushings to be inserted. Extending upward from the bed 10 and arching over the bed is a yoke 14, which may be of any suitable construction, but which is shown as being 60 U-shaped in form and having the lower ends of its arms integrally connected or formed with the bed 10, the bed 10 and the yoke 14 being cast in one piece. At the upper end of the yoke the yoke is formed with a vertically extending screw-threaded passage 15, which is in exact alignment with the opening 13.

Operating within the screw-threaded passage 15 is a presser screw 16, whose lower 75 end is reduced as at 17, this reduced lower end being round in cross section. The upper end of the screw 16 is formed with a head 18, through which passes the handle 19.

Designed to operate in conjunction with the presser screw 16 is a head 20, whose lower end is reduced in diameter, as at 21, so as to fit within a bushing, while its upper end is formed with a socket 22 having a diameter equal to the diameter of the reduced portion 17 of the screw 16. Also used in conjunction with the screw 16 and the head 20 is an extension piece 23, which is formed at its upper end with a socket 24 whose diameter is equal to the diameter of 80 the reduced portion 17 of the screw 16 and which, at its lower end, is reduced in diameter as at 25 to fit within the socket 22 of the head 20. In actual use this extension piece 23 will be about four inches long more or less.

Also used in conjunction with the elements heretofore described and for the purpose of supporting the wall of the piston against deformation due to pressure applied 100 thereto, is a supporting block formed in two sections 26 and 27. Each of these sections is formed with a central recess 28 upon its outer face. Each section is also formed with a dowel pin 29 upon its inner face and opposite the dowel pin with a mortise 30 to receive the corresponding pin on the opposite section. The confronting faces of the two sections are each formed with a tapering screw-threaded approximately semi-circular 105 110

recess 31 extending diametrically across the sections, and coacting with the sections is a tapered screw 32 having a shank 33 and a handle 34. It will be seen that when the 5 tapered screw 32 is inserted in the screw-threaded recess 31 in the sections, the sections being forced against each other, that a rotation of the screw in one direction will cause the sections to expand.

16 The operation of removing bushings from pistons is attended with considerable difficulty, for the reason that the bushings are very tightly engaged with the inwardly extending hubs of the piston and the pressure 15 exerted upon the bushings in the attempt to hammer the bushings out is very liable to deform the whole of the piston. Furthermore, in inserting new bushings, there is 20 liability of overturning the bushings or deforming them. My machine is designed to 25 avoid this and permit of the ready removal and ready replacement of the bushings, without any chance of deforming either the pistons or the bushing itself.

26 In order to remove old bushings from a piston, the piston A is placed upon the seat 11 in the position illustrated in Fig. 1, with the hubs *a* extending vertically and with the lower bushing B disposed directly over the 30 opening 13. The head 20 is then disposed within the piston with its reduced end 21 disposed within the bushing B, the shoulder 21^a resting upon the upper edge of the bushing. The extension piece 23 is then passed 35 downward through the upper bushing and into engagement with the upper end of the head 20. The screw 16 is then turned until its reduced end 17 engages in the socket 24 in the upper end of the extension piece 23 40 and then as the screw is further turned, the lower bushing B will be forced out of its corresponding hub. When the lower bushing B has been removed, the piston is reversed upon the bed so that the hub, from 45 which the bushing has been removed, is uppermost and the operation is repeated for the second bushing.

When it is desired to replace the bushings, the supporting member, composed of the 50 sections 26 and 27, is inserted within the piston with its recesses 28 in alinement with the hubs, and then the screw 32 is screwed inward until the sections 26 and 27 are expanded firmly against the inner ends of the 55 hubs B in the position shown in Fig. 2. Thus the wall of the piston is fully supported against any deformation. The new bushing B' is then disposed at the entrance of the uppermost hub and the head 20 is disposed 60 upon this bushing. The screw 16 is then screwed downward against the head 20 and this screwing action forces the head 20 downward and forces the bushing into place within the corresponding hub. When the 65 bushing is fully in place and bearing against

the face of the section 26, then the screw 16 is released, the piston is turned over, and the second bushing is put in place.

It will be seen that in removing the bushings, the pressure is exerted from the inner 70 end of the bushing outward and the piston is fully supported by the bed 11, so that there cannot possibly be any deformation of the piston. The pressure is exerted entirely upon the bushing and not upon the piston in 75 any way. It will also be seen that when a new bushing is inserted the piston is fully supported against any possible depression or deformation by the expanded blocks 26 and 27. With this device it is a very easy 80 matter to remove the bushings of wrist pins and replace these bushings. It is also obvious that the device may be used for the purpose of initially inserting new bushings into pistons. 85

While I have illustrated a particular form of my invention, which I have found in practice to be very effective, I wish it understood that the device may be modified in many respects without departing from the 90 scope of the appended claims. It will be seen that the member 16 constitutes a presser or plunger and that it may be forced downward toward the bed by any suitable means which will be effective in forcing out the 95 bushing. It will further be seen that while I have shown a particular form of means for supporting the piston wall against deformation when a bushing is being inserted that this means might be modified in many 100 respects.

Having thus described my invention, what I claim is:—

1. A device of the character described comprising a bed for supporting a piston, 105 means adapted to be disposed within the piston for supporting it against deformation, and means mounted above the bed for forcing a bushing into place within the piston.

2. A device of the character described 110 comprising a bed formed with a piston seat and with an opening extending through the piston seat, a yoke mounted upon the bed and extending above it, a screw-threaded plunger mounted in said yoke in alinement 115 with the opening in the bed, and a detachable head larger in diameter than the plunger and having a diametrically reduced circular extremity adapted to be inserted within a bushing, the opposite face of the head 120 being formed with a socket to receive the lower end of the plunger.

3. A device of the character described comprising a bed formed with a piston seat and having an opening extending through 125 it, a yoke extending upward over the bed, a plunger mounted in the yoke for movement toward and from the bed and disposed in alinement with the opening through the bed, an extension piece having a socket at 130

its upper end to engage the lower extremity of the plunger and being reduced in diameter at its lower end, and a head coacting with the extension piece and having a reduced lower end adapted to fit within a bushing the upper face of the head being formed with a socket to receive the reduced end of the extension piece.

4. A device of the character described comprising a bed formed with a piston seat, a yoke arching over the bed and having a passage disposed over the center of the piston seat, a plunger movable through the passage in the yoke and toward or from the bed, supporting members adapted to be disposed within the piston, and means for expanding said members against opposite portions of the piston wall.

5. A device of the character described comprising a bed formed with a piston seat, a yoke arching over the bed and having a passage disposed over the center of the piston seat, a plunger movable through the passage in the yoke and toward or from the bed, supporting members adapted to be disposed within the piston, means for expanding said members against opposite portions of the piston wall, and a head having a socket in its upper face adapted to receive the lower end of the plunger, the lower end of the head being reduced and adapted to be inserted within the bushing.

6. Means for removing and replacing the bushings of wrist pins in hollow pistons, comprising a bed having a transversely concave piston seat, the under face of the bed

being cut away and there being a passage from the under face to said seat, a yoke integral with the bed and arching over it and having a screw-threaded passage disposed in alignment with the opening through the bed, a screw-threaded plunger engaging said passage and having a reduced lower end, a head having a diameter larger than the diameter of the plunger and having a reduced lower end adapted to be inserted within the bushing, and having a socket on its upper face, an extension piece having a diameter less than that of the head and reduced at its lower end to fit within the socket of the head, and having a socket at its upper end adapted to receive the lower end of the plunger, and means for holding a piston against deformation while a bushing is being inserted, comprising coacting block sections held from lateral movement with relation to each other but adapted to move toward or from each other and formed upon the inner faces with tapering screw-threaded registering grooves, and a tapering screw adapted to be inserted between said block sections and in said grooves to thereby force the block sections outward and against the ends of the inwardly projecting wrist pin hubs of a piston.

In testimony whereof I hereunto affix my signature in the presence of two witnesses.

FRANK C. JONES.
